UNITED STATES PATENT OFFICE.

GAYLARD MACK, OF PENDLETON, ENGLAND, ASSIGNOR TO THE F. REDDAWAY & COMPANY, LIMITED, OF SAME PLACE.

BELTING.

SPECIFICATION forming part of Letters Patent No. 650,977, dated June 5, 1900.

Application filed January 24, 1899. Serial No. 703,284. (No model.)

To all whom it may concern:

Be it known that I, GAYLARD MACK, weaving manager, a subject of the Queen of Great Britain and Ireland, residing at 41 Rockley street, Broughton road, Pendleton, in the county of Lancaster, England, have invented certain new and useful Improvements in and in the Manufacture of Woven Driving-Belting, (for which I have made application for 10 patents in Great Britain, No. 6,475, dated March 17, 1898, and No. 16,509, dated July 29, 1898,) of which the following is a specification.

My said invention relates to improvements 15 in and in the manufacture of woven driving-belting. Such driving-belting is woven in varying widths to suit requirements and is cut into desired lengths and the ends connected by fasteners. It is found in practice 20 that various objections are inherent to this method. For instance, to cope with the demand for belting of the many different widths large stocks of such varying widths of belting must be kept in hand. Further, the strength 25 of the belting is weakened at the point of connection, and this weakness is difficult to overcome without destroying the flexibility of the belt. These objections are fully met and 30 overcome by my invention, which is illustrated in the accompanying drawings.

Figure 1 is a plan view of a part of a belt embodying my invention. Fig. 2 is a cross-section of Fig. 1. Figs. 3 and 4 represent a modified form of my invention. Fig. 5 shows 35 the method of connecting the ends of a belt composed of strips.

The edges of the strips *a* are woven in such a manner that they may be readily sewed together with or without the stitches going 40 through the body of the belt. To effect this, I weave the strips *a* so that any number of warp or weft threads, or both, are woven together at each edge, (or one edge only, as required,) so as to form a loop-weave *b*, as shown 45 clearly in Fig. 1. The loops *b* are then threaded, as shown, and may be drawn more or less tightly together, as shown in Fig. 2.

Instead of a loop-weave the edges may be woven more loosely than the body of the belt

by any suitable weave, and the edges are then 50 sewed together. To effect this, I place the strips to be connected one upon the other, as shown in Fig. 3, and secure the edges together by hand-sewing or by a suitable machine, the 55 stitches being passed through the edges of the strips *a* or through the body thereof. Thus not only is it possible to readily construct belts of varying widths to order from such strips, but the connection of such a belt can be easily effected to break joint. For instance, suppose a belt of thirty feet in length 60 be built up from three strips. The ends of the strips where connected may be separated from each other a distance of ten feet apart. This is indicated in diagrammatic form in Fig. 5. 65 The strength of the belt is increased by thus breaking up the points of connection, and the flexibility of the belt is not so much impaired as in the case with methods at present in use. Moreover, where metal fasteners are used the 70 weight of the fasteners is distributed over the length of the belt, and any slipping of the belt on the pulley, due to the pressure of a number of fasteners at one point, is also avoided.

75 The form shown in Fig. 4 and that shown in Fig. 5 are similar in that the loops of Fig. 5 are in effect tongues of reduced thickness to form the means of attachment.

The threads or stitches securing the two 80 parts together are depressed in respect to the surface of the belt, and thus are not subjected to frictional wear from the belt-wheel.

I declare that what I claim is—

A belt composed of a plurality of strips of 85 woven material having their longitudinal selvage edges united by stitches, said stitches engaging parts of the weave of said selvage edges and being depressed in relation to the working surfaces of the strips, substantially 90 as described.

In witness whereof I have hereunto set my hand in presence of two witnesses.

GAYLARD MACK.
